UNITED STATES PATENT OFFICE.

RALPH W. BORCHERT, OF ST. LOUIS, MISSOURI.

SWITCH.

No. 909,742.

Specification of Letters Patent.

Patented Jan. 12, 1909.

Application filed December 16, 1907. Serial No. 406,660.

To all whom it may concern:

Be it known that I, RALPH W. BORCHERT, a citizen of the United States, residing at St. Louis, Missouri, have invented a new and useful Switch, of which the following is a specification.

This invention relates to switch mechanisms for incandescent electric lights; and it consists of the novel construction, combination and arrangement of parts hereinafter shown, described and claimed.

The object of the invention is to produce an efficient switch mechanism for use in connection with electric lighting means, in which the switch mechanism is actuated by a revoluble ring encircling the switch or arranged in such relation thereto that, when turned a proper distance, it will cause the switch terminals to contact thereby completing the lighting current; and when turned further it will permit the spring portion of the terminals to snap out of contact with the stationary portion, thereby breaking or opening the circuit. The ring is revoluble in either direction to accomplish the switching operations.

Other objects, and manifold conveniences and advantages of the invention and its construction, will be obvious from the following description thereof, reference being made to the accompanying drawing in which:

Figure 1 is a side elevation of a switch socket used in connection with incandescent electric light bulbs or lamps showing my invention embodied in such mechanism. Fig. 2 is a similar view showing the actuating ring in section and disclosing the spring terminal of the switch. Fig. 3 is a view of the switch mechanism, the insulated inclosure being removed to disclose the parts of the switch. Fig. 4 is a longitudinal sectional view, illustrating the arrangement of the actuating ring relative to the switch terminals. Fig. 5 is a cross sectional view on the line 5—5 of Fig. 1. Fig. 6 is a perspective view of a portion of the switch inclosed showing a support for the actuating ring. Fig. 7 is a perspective view of the part in the switch to which one of the wire terminals is attached and which is also the spring portion of the terminal.

The drawings show the invention embodied in a switch for a single lamp or bulb, but it is obvious that it may, with equal efficiency be applied as the actuating mechanism for other species of switches.

The part 1 is an insulated cover which partially incloses the terminal support 2 to which the socket 3 is attached in any preferred manner. A terminal member 4 is fastened to the support 2 and has a projection 5 to which the end of one of the wires 6 is attached. The socket 3 is insulated from the member 4. The other wire 7 is connected to a member 8 which projects through a notch, or opening in the socket 3 and terminates in such position that the contact point of the bulb or lamp will engage or contact therewith when in its home or rest position. The member 4 has a spring projection 9 which terminates adjacent to, but normally out of contact with, the end of the socket 3. To complete the circuit the end of the terminal projection 9 is pressed against the socket 3 which is on the line of the wire 7 through medium of the member 8 and the bulb contact point and filament. The entire switch 1 is constructed is inclosed within a suitable insulated case 10 for obvious reasons.

The case 10 has an opening 11 through which a knob or projection 12 on the terminal 9 projects, said knob being of suitable non-conducting material. A ring 13 encircles the case 10 resting on projections 14 on said case and shielded from above by a flange 15 on the part 1. Within the inner side of the ring 13 there is a series of notches 16 of such size and depth that the knob 12 may extend thereinto to permit the terminal 9 to remain out of contact with the socket 3. The surfaces of the ring which are between the notches 16 are of sufficient elevation or dimensions so that when the ring is revolved to rub either one of said surfaces against the knob 12 it will push the terminal 9 against the socket 3, thereby completing the circuit. Obviously the ring 13 may be revolved in either direction to accomplish this switching. The periphery of the ring may be grooved or knurled, as shown in Fig. 1, for well known reasons.

A switch mechanism of the character described is of maximum simplicity and most easily operated. It may be grasped in any accessible position of the lamp or bulb and avoids the inconvenience in darkness of searching for the operating means after finding the socket as is necessary in that type of switches which employ keys for operating the switch.

I am aware that there may be many variations from the combination herein illustrated and described without in the least departing from the spirit and scope of the invention.

5 I do not restrict myself to exact parts or specific arrangement but

What I claim and desire to secure by Letters Patent is:

10 1. A switch for electric light lamps comprising a case, a spring terminal in said case, a revolute ring encircling said terminal and having recesses on its inner side, and an element separate from said ring intermediate of said ring and said terminal whereby the 15 latter will be operated when the ring is revolved in either direction, substantially as specified.

10 2. A switch for electric light lamps comprising a case, a spring member mounted 20 therein on a stationary support, a contact member for said spring member, a ring revolute in either direction encircling said spring member and contact member, and means whereby said ring when rotated in 25 either direction will actuate said spring member against the contact member, substantially as specified.

3. A switch comprising a stationary terminal, a stationary support, a spring terminal 30 attached to said support, and a revolute ring encircling said terminals and arranged to actuate the spring terminal when rotated in either direction, substantially as specified.

35 4. A switch for electric light lamps comprising a case, a support in said case, a spring terminal attached to said support, a stationary terminal, a ring encircling said terminals and having a series of recesses therein, and an element detached from said 40 ring between said ring and said spring terminal whereby the latter will be actuated when said ring is revolved in either direction, substantially as specified.

5. The combination with an electric light 45 lamp socket, and a terminal spring attached to a stationary support, of a ring encircling and revolute entirely around said socket and constituting a hand-hold arranged to actuate said terminal spring when revolved 50 in either direction, substantially as specified.

6. A switch for electric light lamps comprising a socket, a terminal in said socket to be in permanent contact with the contact point of the lamp, a terminal operable to 55 contact with the socket to complete the circuit with the lamp filament, and a ring en-

circling and revolute in either direction entirely around said socket and arranged to actuate said last-named terminal as required to complete the circuit, substantially as specified. 60

7. The combination with the switch having a spring terminal, of a ring separate from said terminal encircling the switch and operable equal distances in either direction to 65 make contact of the terminal to complete the circuit, substantially as specified.

8. The combination with the switch having a spring terminal, and a non-conducting element connected with said spring terminal 70 of a revolute ring separate from said spring terminal encircling the switch and operable in either direction against said non-conducting element effectively to actuate the spring terminal to complete the circuit, substantially as specified. 75

9. The combination with the lamp socket and the switch having a spring terminal, of a ring detached from the spring terminal encircling and revolute entirely around the 80 socket in either direction, and means whereby the ring when revolved a given distance in either direction will operate said spring terminal, substantially as specified.

10. The combination with the lamp socket 85 and the spring terminal, of a ring encircling the socket and revolute in either direction, and means whereby the ring when revolved a given distance in either direction will operate said spring terminal, substantially as specified. 90

11. A switch for electric light lamps comprising a socket, a terminal in said socket to be in permanent contact with the contact point of the lamp, a terminal operable to 95 contact with the socket to complete the circuit with the lamp filament, a ring encircling said socket and being revolute entirely around said socket in either direction, and means whereby said ring will operate said last-named terminal a plurality of times during each revolution, substantially as specified. 100

In testimony whereof, I hereunto affix my signature to this specification this 14th day 105 of December, 1907, in the presence of two witnesses.

RALPH W. BORCHERT. [L.S.]
